ATTORNEY

UNITED STATES PATENT OFFICE.

PETER RASMUSSEN, OF NEW YORK, N. Y.

YARN-FASTENER FOR REEL-MILLS.

1,360,018.

Specification of Letters Patent. Patented Nov. 23, 1920.

Application filed May 13, 1920. Serial No. 380,965.

To all whom it may concern:

Be it known that I, PETER RASMUSSEN, a citizen of the United States, and resident of New York city, in the county of Bronx and

5 State of New York, have invented certain new and useful Improvements in Yarn-Fasteners for Reel-Mills, of which the following is a specification.

This invention relates to improvements in 10 fastening means used in connection with the reels in yarn winding machines usually called reel mills.

The object of the invention is to provide a snap fastener adapted to be secured to the 15 reel blades whereby to enable the operators to quickly and conveniently secure the end of the yarn to the reel, the yarn being wound into skeins on the reel and being unwound from spindles.

20 The accompanying drawing illustrates the fastener and its application to the reel mills.

Figure 1 is a diagrammatic transverse sectional view illustrating so much of a reel mill as is necessary for an understanding of 25 the invention.

Fig. 2 is a fragmentary view of parts shown in Fig. 1 looking in the direction of arrow 2 in said figure.

Fig. 3 is a view of my improved fastener 30 attached to a reel blade.

Fig. 4 is a face view of the fastener.

Fig. 5 is an end view thereof.

Referring first to Figs. 1 and 2 the reference numeral 6 indicates in general the 35 framework of a reel mill. Only the one side of the reel mill is shown, the two sides being alike in construction. 7 indicates a centrally located driving drum running the length of the mill and which drives the 40 spindles 8 and 9 by means of belts 10 and 11. On the spindles are placed spools of yarn, such as silk for instance, marked 12 and 13. The yarn passes upward from the spools, through eyes 14 secured to a reciprocating 45 bar 15. The reciprocating means are not shown as they are well known in the art.

The numeral 16 denotes the reel in general comprising a shaft 17 which suitably supports the reel blades 18, which are generally 50 made of wood.

It will be understood that a reel mill is a rather long machine and may have a plurality of reels placed endwise to each other and that the purpose of the mill is to wind 55 the yarn on the reels into skeins and at the same time twist the yarn into final different

sizes and grades as may be desired. When the skeins have been wound upon the reels, they are taken off and sold as skeins of 60 yarns, silk, cotton or other kinds.

In the operation of the mill, the operator receives the spools of yarn and places them on the spindles, then runs the free ends of the spool through the twisting members 19 and then upward through the eyes 14. 65 Thereafter, and this is the usual practice, the operator throws the end of the yarn around the nearest blade of the reel, which is then rotating, and quickly ties the yarn to the blade. In doing this, a rather large 70 loop of yarn is made around the reel blade and as much as half a yard of yarn may be wasted in tying the yarn to the reel. Inexperienced operators may also be hurt by the rotating reel or get the fingers caught 75 therein. Altogether the practice is slow and wasteful. The foregoing is not illustrated in the drawing because it alludes only to what is well known in the art.

The object of this invention is to provide 80 a fastener which may be easily attached to the reel blades and whereby the above objectionable features may be overcome.

The fastener is illustrated in detail in Figs. 3, 4 and 5, and comprises a bracket 85 forming a base 20 with an attaching foot 21 at right angle to the base. The fastener further has an upstanding portion 22 ending in a lip 23 which overhangs the base. 24 is a seat for a rather stiff spring 25 90 which is secured by a screw 26. The spring is so arranged that its end portion 27 bears strongly against the lip 23 and its extreme end 28 barely clears the inside of the upright portion 22. The fastener is secured 95 to the reel blade by one or more screws 29 and is secured to the inner edge 30 of the blade as shown in Fig. 1.

Instead of tying the yarn to the reel, the operator takes the end of the yarn between 100 the hands and quickly snaps it over the lip 23 into the jaw formed between the spring and said lip where the yarn, marked 31, is securely caught. By this fastening means only a very short end of the yarn is wasted. 105 The operation is quickly accomplished and is not attended by any danger to the operator.

I claim:—

1. The combination with a reel of a reel 110 mill, of a fastener adapted to be secured to the blade of the reel, said fastener compris-

ing a bracket portion and a spring portion forming a jaw for attaching the yarn to the said reel.

2. The combination with a reel of a reel mill, of a plurality of fasteners adapted to be secured permanently to the blades of the reel, each of said fasteners forming a spring jaw adapted to grip the free end of the yarn for attaching the latter to the said reel.

10 3. A fastener of the character described comprising a bracket portion and a spring secured to the same to form a jaw in coöperation therewith.

4. A fastener of the character described comprising a bracket having a base and an attaching foot, and a spring secured to said fastener and adapted to form a jaw in coöperation therewith.

5. A fastener of the character described comprising a bracket having a base and an attaching foot, the said bracket further being provided with a lip portion spaced from the said base and a spring secured to the latter and adapted to press against the 25 said lip portion for the purpose set forth.

6. A fastener of the character described

comprising a bracket, means for securing the same to a reel blade, said bracket having an upstanding portion formed with a lip overhanging the said base and a spring secured to the latter and arranged to press against the underside of the said lip for the purpose set forth.

7. The combination with a blade of a reel, of a fastener having a base portion adapted to lie against the face of the reel blade and an attaching foot portion adapted to be secured to the edge of the reel blade, and a spring secured to said bracket and adapted to form a jaw in coöperation therewith.

8. The combination with a reel having reel blades and adapted to rotate, of a fastener adapted to be secured to the blades of the reel, said fastener comprising a base portion and a spring adapted to form a jaw 45 in coöperation with the said base, the said formed jaw being open in the direction of rotation of said reel for the purpose set forth.

Signed at New York in the county of New York and State of New York this 12th day of May A. D. 1920.

PETER RASMUSSEN.
